UNITED STATES PATENT OFFICE.

GEORGE HERBERT GIBSON, OF MONTCLAIR, NEW JERSEY, ASSIGNOR TO COCHRANE CORPORATION, OF PHILADELPHIA, PENNSYLVANIA, A CORPORATION OF PENNSYLVANIA.

DEAERATING WATER.

Application filed April 11, 1921. Serial No. 460,389.

The general object of my present invention is to provide a simple and effective method of, and apparatus for eliminating air from water without requiring the water to be heated above a maximum temperature which is substantially below 212° F., with an effective utilization of exhaust steam available for the purpose in restricted and variable amounts. The invention was primarily devised for, and is especially useful in, treating boiler feed water which is to be preheated in an economizer before being passed into the boiler and where the steam available for use in the deaerating process is ordinarily insufficient to heat the water to a temperature of 212° F., and where at times there may be no steam whatever available for use in the deaerating process. In accordance with the present invention air is removed from the water by passing the latter through a deaerating chamber which is preferably of the open feed water type having an air and vapor space through which the water is passed in finely divided or broken streams and from which air mixed with more or less vapor is withdrawn by a suitable ejector which normally maintains a substantial vacuum in the deaerating chamber. The available steam is passed into the steam and air space of the deaerating chamber. The ejector employed should be of a type and capacity enabling it to withdraw air from the chamber as rapidly as the air is liberated from the water without withdrawing an unduly large quantity of steam when, as may occasionally occur, the amount of steam supplied to the deaerating chamber is sufficient to maintain a pressure therein equal to or exceeding that of the atmosphere.

By proceeding in the manner described, I am able to eliminate all but a very small portion of air or other gases dissolved in the water with apparatus which is relatively simple. With the restricted amount of steam available in the normal contemplated operation of the apparatus the deaerated water will leave the deaerating chamber at a temperature appreciably below 212° F. The available steam no matter how relatively small the amount may be is effectually utilized in heating the water and in facilitating the air removal. The amount of air remaining in the water after the treatment de-

scribed is so small as to be practically unobjectionable either because of its corrosive effect or otherwise for many purposes for which deaerated water is required, but this small air content may be eliminated, if desired, by additional treatment in known ways, as by passing it through a filter of iron filings or the like which may be placed in the lower portion of the deaerating chamber, or by an electrolytic treatment.

The various features of novelty which characterize my invention are pointed out with particularity in the claims annexed to and forming a part of this specification. For a better understanding of the invention, however, and its advantages, reference should be had to the accompanying drawings and descriptive matter in which I have illustrated a preferred form of apparatus.

The one figure of the drawing is a somewhat diagrammatic elevation with parts broken away and in section.

In the drawing A represents a deaerating chamber, which in its general aspects is like an ordinary open feed water heater, having an outlet A' for the treated water, a steam inlet A², and a raw water supply pipe D. The discharge of water into the chamber A through the pipe D is regulated by a valve E which is automatically opened and closed by a float F as required to maintain the proper water level in the chamber A. The outlet E' from the valve E opens into a dip trough C discharging on to the usual splash trays B, as is usual in open feed heaters.

Steam is supplied to the inlet A² from a pipe H through a separator G and, as shown, through a pressure regulating or flow valve I, which is of a known type and serves to prevent the passage of steam into the chamber except when the pressure in the pipe H exceeds the pressure of the atmosphere.

The valve I, as illustrated, is provided with a plurality of ports each controlled by a corresponding valve member I' which is given a closing tendency by a corresponding spring I² and by the pressure of the atmosphere acting against a piston I⁴ working in a piston chamber I⁵ which is open at its outer end to the atmosphere and at its inner side to the outlet chamber of the valve I. The valves I and their pistons I⁴ are of the same diameter so that the valve members

I' are balanced in so far as the pressure in the outlet chamber I'' is concerned. With a valve I of the type illustrated controlling the flow of steam to the chamber A, the latter has no tendency to lower the pressure in the pipe H below the predetermined valve at which the valves I open. This is desirable, for example, where the pipe H receives exhaust steam from auxiliaries which should not be operated under a vacuum or minus pressure, and is desirable also where the pipe receives steam from a source of supply which must take care of steam demands more important than that of the deaerating chamber A. The valve I may be dispensed with in some cases, as when the pipe H leads directly from the exhaust of a steam turbine or other source of steam operating at a pressure below that of the atmosphere.

20 Air is withdrawn from the heater A through an outlet A^e which is connected to the inlet of a steam jet ejector or exhauster K. K' represents the steam supply line to the latter. The ejector outlet K² leads to the upper portion of a gleaner or vapor condenser L which as shown comprises a drum surrounding an enlarged portion D' of the raw water supply pipe D. L' represents an outlet for air and water of condensation from the annular space within the drum L surrounding the pipe D'. The water dripping from the outlet L' passes into a spout M' leading to a float trap M. The latter is provided with an outlet M⁴ leading back to the chamber A, and with a water sealed valve M³ controlled by a float M² and serving to permit the passage of water but not of air into the chamber A through the pipe M⁴.

To guard against an abnormal accumulation of water in the chamber A, an overflow connection A³ is provided. The latter includes a non-return or check valve A⁴ which is water sealed by locating it below the level of the discharge end A⁵ of the outlet connection A³. The chamber A is provided at its upper end with a normally closed vacuum breaking valve O which is connected to a float O' above the normal water level in the chamber A. On a sufficient rise in water level in the chamber A, the float O' opens the vacuum breaking valve O and permits the pressure in the chamber A to build up to that in the atmosphere. When this occurs the excess water in the chamber A will discharge through the connection A³. To eliminate oil accumulating in the separator G, the outlet G' from the latter is connected to a vacuum trap P which may be of the known monteius type, comprising a float actuated valve mechanism for intermittently admitting steam to the trap P to blow out liquid which has accumulated therein without permitting any back flow of liquid or of air into the separator G through the connection G'.

In operation the continuously acting ejector K prevents any appreciable accumulation of air in the steam and air space of the chamber A, and that space will be filled mainly by water vapor, and its temperature and that of the water accumulating in the bottom of the chamber and withdrawn through the outlet A', will correspond approximately to the temperature of saturated steam at the pressure maintained in the upper portion of the chamber A. This pressure will depend of course on the relative amounts of steam and water supplied to the chamber A. Normally it will be appreciably below that of the atmosphere. Under the described conditions of operation the water admitted to the chamber A through the pipe D will liberate all but a relatively insignificant portion of its air content as it passes over the splash trays E and falls from the latter to the bottom of the chamber.

The supply of water to the chamber A is normally regulated by the float F and valve E as required to meet the demand for water withdrawn through the outlet A'. The small amount of steam supplied to the ejector K through the supply pipe K', and the water vapor admixed with the air withdrawn by the ejector K through the outlet A^e are condensed in the condensing space between the pipe D' and the drum L without unduly increasing the temperature of the water passing through the chamber A to the pipe D. The water of condensation issued from the outlet A' is automatically returned to the chamber A through the float trap M and the return connection M⁴.

The contemplated mode of operating the apparatus disclosed insures thorough deaeration of the water, and the delivery therefrom of the deaerated water at a temperature which normally is sufficiently low, say 150° or 160° F., for the effective utilization of an economizer in preheating the water before its delivery to a boiler. Since the normal working temperature in the heater A is appreciably below 212° F., substantial variations in the relative amounts of exhaust steam supply and water to be heated can occur without waste of steam to the atmosphere. Such variations in the relative proportions of steam and air supplied produce consequent variations in the temperature at which the water issues from the deaerating apparatus, but such variations as occur from this cause are relatively unimportant from a practical standpoint when the deaerating apparatus is used in treating boiler feed water for delivery to an economizer, especially since ordinarily in such use the high temperatures would occur under conditions of light load, and the low temperatures under conditions of heavy load when the economizer is most effective and its effective use is most important.

While in accordance with the provisions of the statutes I have illustrated and described the best form and mode of carrying out my invention now known to me it will be apparent to those skilled in the art that formal changes may be made without departing from the spirit of my invention as set forth in the appended claims.

Having now described my invention, what I claim as new and desire to secure by Letters Patent, is:

1. In heating and deaerating water, the method of utilizing steam, normally available in restricted and variable amounts from a source in which a minimum pressure is desirably maintained, to facilitate deaeration and in heating the water, which consists in passing the water through a deaerating chamber in a finely divided form, and supplying steam to said chamber from said source to satisfy the heat absorption capacity of the chamber so far as is possible without reducing the pressure of the steam source below said minimum pressure and without regard to the difference between the pressure of said source and in said chamber, and withdrawing air and vapor from said chamber as required to maintain a pressure therein corresponding approximately to the pressure of the saturated water vapor at the temperature to which the water is heated in said chamber.

2. In heating and deaerating water, the method of utilizing steam normally available in restricted and variable amounts from a source in which a minimum pressure is desirably maintained, to facilitate deaeration and in heating the water, which consists in passing the water through a deaerating chamber in a finely divided form, and supplying steam to said chamber from said source to satisfy the heat absorption capacity of the chamber so far as is possible without reducing the pressure of the steam source below said minimum pressure, withdrawing air and vapor from said chamber as required to maintain a pressure therein corresponding approximately to the pressure of saturated vapor at the temperature to which the water is heated in said chamber, cooling the air and vapor withdrawn from said chamber with the water passing into the chamber, and returning the condensate thereby formed to said chamber.

3. Apparatus for deaerating water comprising in combination a closed chamber having a water inlet and outlet and provisions for regulating the height of water level in the chamber so as to maintain a steam and air space in the upper portion of the chamber, an exhauster for withdrawing air from said steam and water space, a source of steam supply, and means independent of the pressure in said space for regulating the passage of steam from said

source to said space in response to the pressure of the steam in said source of supply.

4. Apparatus for deaerating water comprising in combination a closed chamber having a water inlet and service water outlet and an overflow outlet connection including a non-return valve preventing back flow into the chamber, an exhauster for withdrawing air from the chamber, means normally supplying steam to said chamber in amount insufficient to maintain a pressure in said chamber as high as that of the atmosphere, and a float actuated valve operative on a predetermined increase in height of water level in said chamber to admit air thereto and thereby cause the excess water to discharge through said overflow connection.

5. Apparatus for deaerating water comprising in combination a closed chamber having a water inlet and a water outlet and means for regulating the height of water level in the chamber as required to maintain a steam and air space in the upper portion thereof, an exhauster for withdrawing air from said chamber, and means comprising a steam supply line including an oil separator for supplying steam to said chamber in amount normally insufficient to maintain a vapor pressure in the chamber as high as that of the atmosphere, and provisions including a vacuum trap for discharging liquid from said separator at intervals.

6. Apparatus for deaerating water comprising in combination a closed chamber having a water inlet and outlet and means for regulating the height of water level therein so as to maintain a steam and air space in said chamber, an exhauster for withdrawing air and vapor from said chamber, means for supplying steam to said chamber in amount normally insufficient to maintain a vapor pressure therein as high as atmospheric pressure, and a condenser cooled by the water passing to the water inlet of the chamber and cooling the air and vapor withdrawn from said chamber, and means for returning the water of condensation formed in said condenser to said chamber comprising a float trap connected to said chamber.

7. Apparatus for deaerating water comprising in combination a closed chamber having a water inlet and outlet and means for regulating the height of water level therein so as to maintain a steam and air space in said chamber, an exhauster for withdrawing air and vapor from said chamber, and means including a steam supply pipe and an automatic valve dependent in its operation on the pressure in said pipe but independent of the pressure in said space for supplying steam to said chamber when the pressure in said pipe exceeds a predetermined value.

8. Apparatus for deaerating and heating
